UNITED STATES PATENT OFFICE.

PAUL M. KEMTER, OF CLERMONT, NEW YORK.

COLLAR FASTENER.

1,402,867.

Specification of Letters Patent. Patented Jan. 10, 1923.

Application filed August 28, 1920. Serial No. 406,559.

To all whom it may concern:

Be it known that I, PAUL M. KEMTER, citizen of the United States, residing at Clermont, in the county of Columbia and 5 State of New York, have invented certain new and useful Improvements in Collar Fasteners, of which the following is a specification.

This invention relates to an improved 10 collar fastener and has as one of its principal objects to provide a device of this character which will not become accidentally displaced.

A further object of the invention is to 15 provide a device wherein a collar cannot work loose or out of engagement with the fastener.

And the invention has a still further object 20 to provide a device which may be readily applied and which, when applied, will be neat and attractive in appearance.

Other and incidental objects will appear hereinafter.

In the drawing:

25 Figure 1 is a sectional view showing my improved collar fastener in position securing a collar to the neck band of a shirt, the collar and neck band being conventionally illustrated,

30 Figure 2 is an elevation of the device,

Figure 3 is a perspective view of the device,

35 Figure 4 is a vertical section taken medially through the device, and

Figure 5 is a detail view showing the spring jaw ring of the cap employed.

In carrying the invention into effect, I 40 employ a link 10. This link is preferably formed from a length of suitable resilient wire and the sides thereof are, as shown in Figure 3 of the drawing, bent laterally inward toward each other at a point substantially midway between the ends of the 45 link to provide a medial reduced throat 11.

Further, the sides of the link are, as particularly brought out in Figure 4, curved longitudinally toward each end of the link, said sides being curved in one direction toward 50 one end of the link and in a reverse direction toward the other end of the link so that the ends 12 of the link lie in relatively offset planes. The link ends 12 are bent inwardly at their intermediate portions to 55 ward the throat 11 to provide lateral offsets at the ends of which are defined hinge mem-

bers 13. As will be seen, the link is of such construction that a single length of suitable resilient wire may be readily bent to form the link, the ends of the length of wire preferably meeting at the offset in one end of the shank. Swingingly mounted upon the upper end of the shank is a stud 14 which is formed with a spherically shaped head and is provided with an enlarged annular base 15 adapted to overlie the throat 11 of the link at its rear side. Extending from the base of said stud at opposite sides thereof are parallel tangential arms 16 which, at their free end portions are bent 65 to provide hinge loops 17 embracing the hinge members 13 at the upper end of the link and hingedly connecting the stud therewith. Swingingly mounted upon the lower end of the link is an annular cap 18. At its 70 rim this cap is, as particularly shown in Figure 4, formed with an inwardly directed annular flange 19 and impinging beneath said flange is a split annular jaw ring 20. As shown in detail in Figure 5, said 75 ring is preferably formed from a suitable length of resilient wire and the end portions thereof are bent inwardly in parallel relation to provide a pair of chordally disposed coacting jaws 21 lying at opposite 80 sides of the axis of the cap centrally thereof. These jaws are, of course, designed to receive the stud 14 therebetween resiliently 85 engaging beneath the head of the stud for securing the cap thereon. Extending from 90 the cap at opposite sides thereof are parallel tangential arms 22 the free end portions of which are bent to provide hinge lugs 23 embracing the hinge members 13 at the 95 lower end of the link and hingedly connecting the cap therewith. As will be appreciated, after the stud 14 has been swung downwardly to project through the throat 11 of the link, as shown in Figure 3, the cap may simply be swung upwardly and 100 engaged over the head of the stud.

In Figure 1 of the drawings, I have shown the manner in which my improved collar fastener is applied. In this figure, the neck band of a shirt is conventionally shown at 24 and a collar at 25. Initially, the stud 14 is inserted through the button holes in the overlapped ends of the neck band from the inner side thereof when the link 10 is swung downwardly to overlie the outer side of the neck band. The flaps of the collar are then, in the usual manner, en-

gaged with the stud so that, as shown in Figure 1, the link will thus be disposed between the collar and the neck band, the upper rearwardly curved end portion of the link extending rearwardly over the upper edge of the neck band and the lower forwardly curved end portion of the link extending outwardly beneath the lower edge of the collar. After the collar is secured 10 by the stud the cap 18 is then swung upwardly and engaged over the head of the stud confronting the outer side of the collar so that the cap will thus serve to not only lock the stud engaged through the neck band 15 and the flaps of the collar but will also serve to prevent the flaps of the collar from accidentally working off of the stud. A secure fastening for the collar is thus provided.

Having thus described the invention, what 20 is claimed as new is:

1. A device of the character described including a stud, a cap therefor, and means swingingly connecting the cap and stud and formed to receive the stud therethrough engaged by the cap.
2. A device of the character described including a stud, a cap therefor, and means

swingingly connecting the cap and stud for movement into engagement with each other, one lying at the front of said means and the other at the rear thereof.

3. A device of the character described including a link, a stud swingingly mounted upon one end portion of the link, and a cap swingingly mounted upon the other end portion of the link and movable to engage the stud.

4. A device of the character described including a link having relatively offset ends, a stud swingingly mounted upon one end 40 of the link and movable to a position at the rear of the link projecting therethrough, and a cap swingingly mounted upon the other end of the link and movable to a position in front of the link engaging the stud. 45

5. A device of the character described including a link, a stud having arms hingedly engaged with one end of the link, and a cap having arms hingedly connected with the other end of the link and movable to 50 coact with the stud.

In testimony whereof I affix my signature.

PAUL M. KEMTER. [L. s.]
